United States Patent Office

Des. 210,521
Patented Mar. 19, 1968

210,521

TRACTOR

Henry Dreyfuss, South Pasadena, and James Mervyn
Conner, Glendale, Calif., assignors to Deere & Com-
pany, Moline, Ill., a corporation of Delaware

Filed Sept. 1, 1967, Ser. No. 8,469

Term of patent 14 years

(Cl. D14—3)

FIG. 1

FIG. 2

FIG. 3

FIG. 4

FIG. 5

FIG. 1 is a perspective view taken from the left front side of the tractor.

FIG. 2 is a perspective view taken from the right rear side of the tractor.

FIGS. 3, 4, and 5 are side, front, and rear views thereof.

The dominant features of our design reside in the portions shown in full lines.

We claim:

The ornamental design for a tractor, as shown and described.
